(57) **CLAIM**

The ornamental design for a foldable slasher, as shown and described.

DESCRIPTION

FIG. 1 is a front view of a foldable slasher in a wings lowered configuration.

FIG. 2 is a rear view of the foldable slasher of FIG. 1.

FIG. 3 is a top view of the foldable slasher of FIG. 1.

FIG. 4 is a bottom view of the foldable slasher of FIG. 1.

FIG. 5 is a left side view of the foldable slasher of FIG. 1.

FIG. 6 is a right side view of the foldable slasher of FIG. 1.

FIG. 7 is a perspective view of the foldable slasher of FIG. 1.

FIG. 8 is a front view of the foldable slasher in a wings raised configuration.

FIG. 9 is a rear view of the foldable slasher of FIG. 8.

FIG. 10 is a top view of the foldable slasher of FIG. 8.

FIG. 11 is a bottom view of the foldable slasher of FIG. 8.

FIG. 12 is a left side view of the foldable slasher of FIG. 8.

FIG. 13 is a right side view of the foldable slasher of FIG. 8.

FIG. 14 is a perspective view of the foldable slasher of FIG. 8.

FIG. 15 is a front view of the foldable slasher in a one wing lowered configuration.

FIG. 16 is a rear view of the foldable slasher of FIG. 15.

FIG. 17 is a top view of the foldable slasher of FIG. 15.

FIG. 18 is a bottom view of the foldable slasher of FIG. 15.

FIG. 19 is a left side view of the foldable slasher of FIG. 15.

FIG. 20 is a right side view of the foldable slasher of FIG. 15; and,

FIG. 21 is a perspective view of the foldable slasher of FIG. 15.
